UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

METHOD OF CRACKING HYDROCARBONS.

1,347,568.

Specification of Letters Patent. Patented July 27, 1920.

Application filed February 12, 1919. Serial No. 276,677.

To all whom it may concern:

Be it known that I, FRANK E. WELLMAN, a citizen of the United States, residing at Kansas City, in the county of Wyandotte, 5 State of Kansas, have invented certain new and useful Improvements in Methods of Cracking Hydrocarbons, of which the following is a specification, reference being had therein to the accompanying drawing.

10 My invention relates to processes for the treatment of hydrocarbons, especially heavy petroleum distillates consisting almost entirely of the paraffin series, to obtain lighter products suitable for motor fuel. The present invention is a specific modification of 15 that disclosed in my copending application Serial No. 259,656, filed October 25, 1918.

The object of the present invention is to provide a process whereby the percentage 20 of yield of commercial gasoline or motor fuel may be increased without a substantial increase in the pressure used. I attain this object by the use of a certain relation between the volume of the oil under treatment and the space above in the cracking retort. My experiments show that with 25 heavy petroleum distillate a charge equal to 10 per cent. of the volume capacity of the retort gives a maximum yield of product at any given pressure. Less amount charged into the container involves difficulty from overheating of the container since there is not enough oil on the bottom to prevent overheating the metal.

30 My invention may be carried out by the use of an apparatus as typified by that illustrated in the accompanying drawing.

The drawing is a diagrammatic view showing the essential apparatus elements.

35 In the drawing 5 indicates the supply pipe leading from a suitable source of supply to a pump 6 discharging through a suitable valve 8 and pipe 9 into a measuring tank 10, the pump being operated by a suitable driving mechanism not shown. A gage glass 11 is provided for the measuring tank and also an air reservoir 12 connected with the tank through a pipe 13 and supplied by a suitable constant pressure 40 pump 14. The measuring tank 10 discharges at its lower end through a charging pipe line 15 into the cracking retort 16, the bottom of the measuring tank being provided with a suitable float valve 15^a or 45 other means to prevent air from passing

into the cracking tube 16 upon emptying of the tank. A stop valve 17 and pop valve 18 are connected in the charging pipe line 15 as well as a pair of check valves 19 and 20 arranged to prevent back pressure from 50 the cracking tube. The cracking tube is constructed so as to resist the cracking temperature and pressure used, both of which in this system are relatively high.

The discharge end of the cracking tube 55 16 is provided with a suitable ball float valve 21 for the purpose of retaining some gas pressure in the tube after discharge of the liquid. A discharge line 22 leads from the discharge end of the cracking tube 70 24 through cooling coil 23 to a receiving tank 24. Included in the discharge line between the float valve 21 and the cooling coil 23 is a trip valve 25 arranged to be opened when tripped by a spring so as to effect a quick 75 opening, the valve stem being provided with a trip catch operated by a handle 26, the valve being set at closed position against the tension of the spring by means of the setting handle 27. The receiving tank 24 is 80 supplied with suitable pressure and vacuum relief valves 28 and 29 respectively, and a discharge pipe 30 with a stop valve 31. The cracking tube 16 is mounted in a suitable furnace 32 provided with a source of 85 heat such as the burner 33. The cracking tube 16 is also provided with a suitable pressure gage 34 and temperature indicating device 35.

The operation of the system is as follows:

The furnace having been started to heat the cracking tube, the measuring tank 10 is filled with the required amount of oil, not exceeding in volume 10 per cent. of the volume of the cracking tube 16 after which the valve 17 is opened, permitting the measured charge of oil to be forced out of the measuring tank by compressed air from the reservoir 12 and through the charging line 100 15 into the cracking tube 16. The cracking tube 16 is now charged with a predetermined volume of oil under pressure and the valve 17 is now closed. Immediately upon closure of the valve 17, the pressure in the 105 cracking tube begins to rise due to continued heating of the oil. This continues until cracking begins, when the temperature of the hydrocarbons becomes substantially constant, while the pressure continues 110

to rise. The temperatures employed range between 750° F. and 900° F. and the pressures between 100 and 600 pounds to the square inch. When the pressure finally reaches the maximum point, the valve 25 is tripped, which permits the contents of the cracking tube to be forcibly discharged out through the chamber of the float valve 21 and the discharge line 22 into the cooling coil 23. This forcible discharge carries with it any carbon or other precipitate that might have formed in the tube or other parts of the apparatus in its path. The mixture of liquids and vapor cooling and condensing in the cooling coil 23 passes on to the receiving tank 24. As the cracking tube discharges, the float valve 21 operates to trap some of the gas in the crack-

ing tube. The trip valve 25 is then set in closed position and the operation repeated. 20

Having thus described my invention what I claim and desire to secure by Letters Patent is:

The process of treating hydrocarbon oil which consists in heating the same to a high 25 temperature and under a high pressure in a retort containing a volume of the hydrocarbon oil equal to ten per cent. of the total volume of the retort with gas under pressure filling the retort over the oil, blowing out the cracked product under pressure, and trapping back the gas so as to retain it in the retort. 30

In testimony whereof I affix my signature.

FRANK E. WELLMAN.
